WILLIAM H. ADAMS, OF KENYON, RHODE ISLAND.

MATERIAL FOR USE IN MAKING GEARS AND SIMILAR OBJECTS.

Application filed February 3, 1927. Serial No. 165,747.

This invention relates to a fibrous compound for use in making gears and similar articles. One way which has commonly heretofore been employed for making material for this purpose has been to assemble layers of textile fabric, either woven fabric or knitted fabric, to form a blank of the required shape, the layers being saturated with compounds or solutions that are capable of being converted into hardened insoluble or infusible artificial resin by a suitable treatment and then subjecting the assembly to such treatment. For instance, a blank for a gear may be made by assembling in axial relation a plurality of annular or circular pieces of fabric cut from a web previously saturated with a filler or strength-giving ingredient, such for instance as synthetic, condensed or polymerized resin, although any suitable binder or strength-giving element may be employed, a suitable number of these pieces being used to make a gear blank of the desired thickness. Where the gear blank is thus made of layers of woven textile fabric this fact and the right-angular arrangement of the warp and filling threads of each layer is apt to produce planes of weakness in the completed article.

My present invention has for its object to provide a novel fibrous blank which may be used for gears or for other articles but which is free from such lines of weakness and which is so constructed that its inherent strength is uniform in every direction with no natural cleavage planes or lines of weakness.

This end is accomplished by forming a blank from hard fibrous threads or cords which are wound or assembled to form a blank or article of the desired shape and with the strands of the cord or thread assembled in layers, each cord having a zig-zag course in its layer and the strands of one layer having a diagonal arrangement with reference to the strands of the adjacent layer.

A blank having this construction and which has been treated with the binding material is free from any natural lines of weakness or planes of cleavage and is equally strong in every direction.

In order to give an understanding of the invention I have illustrated in the drawings a selected embodiment thereof which will now be described after which the novel features will be pointed out in the appended claims.

Fig. 1 is a perspective view of a blank embodying my invention;

Fig. 2 is a diagrammatic view illustrating how the strand or cord may be wound to form the blank.

In Fig. 1 I have shown a cylindrical member 1 which may be considered as a gear blank and from which a gear may be cut. This is formed by winding a hard twisted cord or thread on a revolving core or center 2, said cord being traversed in the direction of the axis of the revolving core as it is being wound and also being preferably wound under a heavy tension.

Fig. 2 illustrates diagrammatically the manner in which the cord is laid. Each turn of the cord as it is wound will have a zig-zag course and the adjacent turns of the cord have a parallel arrangement so that the points 3 where the parallel strands or turns 4 reverse their direction have a progressive position circumferentially of the cylindrical member 1.

A blank may thus be formed by winding a single individual strand or cord on the core 2 and when completed the article may be considered as comprising a plurality of layers, each of which is composed of strands lying in parallelism and each strand having a zig-zag course in the layer. The strands of one layer 5 will have a diagonal arrangement with reference to the strands of the adjacent layer 6. A cord wound in this way makes a very compact, solid and interlocking structure with the turns of the cord running diagonally.

In the complete structure the different turns of the wound cord are bound together by a cementitious binder of some suitable character, such for instance as synthetic, condensed or polymerized resin, the cord being saturated with this binder. The complete article may be formed from an unsaturated cord which is passed through an impregnating solution of the binder as the winding takes place, or the article may be wound from a previously saturated cord or it may be wound from a dry unimpregnated cord and the wound assembly afterwards submitted to proper treatment for saturating it with the binding solution. In the latter case it will be preferable to subject the article to the action of a vacuum for removing the entrained air and then to submit it to proper treatment for saturating it with the cementi-

tious binder. Any desired method of securing complete saturation of the article may be employed, however, without departing from the invention.

5. An article made in this way is a compact, solid and dense block formed of a spirally and diagonally wound fibrous cord which is bound together by condensed or polymerized resin or some other suitable binding agency.
10. A blank such as shown in Fig. 1 may be machined in any usual way to form gears or any other objects and because of its internal structure it has great strength and is free from natural cleavage planes or lines of weakness.
15. Owing to the great strength of the original cord and the various directions in which the fibres run due to the twist in the cord and the diagonal and recrossing superposition of the progressively wound layers, the binding fibres are extending in every direction and there are no lines of weakness such as might exist in a blank made from layers of woven fabric assembled into cylindrical form wherein the threads, the warp and the filling of the fabric run in two right angular directions only in each layer.

A blank having a construction embodying my invention is adapted to resist strain or wear equally well in any direction and it is admirably suited for the formation of gears and other similar objects.

I claim:

35. 1. A blank from which gears may be cut composed of superposed layers each formed of a plurality of strands of fibrous hard twisted cord, each strand having a zig-zag course in the layer, the strands in each layer having a diagonal arrangement relative to those of an adjacent layer, said strands being saturated with and bound together under tension by synthetic resin, and the whole forming a rigid non-yielding structure.
40. 2. A blank from which a gear may be cut or various articles may be made, formed of a

continuous hard twisted fibrous cord wound to present superposed layers each layer having parallel portions of said cord in contact, and with any portion of the cord in one layer having a diagonal arrangement with respect to the portions of the cord with which it contacts in an adjacent layer, said wound cord being saturated with and the separate turns thereof being bound together by a solid cementing composition all portions of the cord being under tension.

55. 3. A blank from which a gear may be cut or various articles may be made, formed of a continuous tensioned hard twisted fibrous cord wound to present superposed layers each having parallel portions of said cord in contact and with any portion of the cord in one layer having a diagonal arrangement with respect to the portions of the cord with which it contacts in an adjacent layer, said wound cord being saturated with and bound together by synthetic resins.

60. 4. A gear blank composed of a mass of synthetic, condensed or polymerized resins containing continuous layers of tensioned fibrous cord, each layer comprising connected parallel turns having a zig-zag arrangement.

65. 5. A blank composed of a mass of synthetic, condensed or polymerized resins containing continuous layers of parallel reversely diagonal wound turns of tensioned fibrous cord.

70. 6. A gear blank composed of a mass of synthetic, condensed or polymerized resins containing continuous layers of tensioned fibrous cord, each layer formed of parallel turns of cord having a zig-zag arrangement with any portion of each turn extending diagonally of the turns of an adjacent layer with which it contacts.

75. In testimony whereof, I have signed my name to this specification.

WILLIAM H. ADAMS.
